(57) **CLAIM**
The ornamental design for a LED spot light, as shown and described.

DESCRIPTION

FIG. 1 is a perspective view of LED spot light showing my present design;
FIG. 2 is a front view thereof;
FIG. 3 is a rear view thereof;
FIG. 4 is a left side view thereof;
FIG. 5 is a right side view thereof;
FIG. 6 is a top view thereof;
FIG. 7 is a bottom view thereof; and,
FIG. 8 is a rear perspective view of a LED spot light, showing my present design in an upside down position.
The broken lines in the drawing depict portions of the LED spot light that form no part of the claimed design.
